By his Attorney, James Hamilton

UNITED STATES PATENT OFFICE.

WILLIAM EDWARD BOEHCK, OF JERSEY CITY, NEW JERSEY.

HOISTING MECHANISM.

1,235,647.

Specification of Letters Patent.

Patented Aug. 7, 1917.

Application filed December 26, 1913. Serial No. 808,632.

To all whom it may concern:

Be it known that I, WILLIAM EDWARD BOEHCK, a subject of the Emperor of Germany, residing in Jersey City, in the county 5 of Hudson and State of New Jersey, have invented certain new and useful Improvements in Hoisting Mechanisms, of which the following is a specification, reference being had to the accompanying drawings.

10 This invention relates to improvements in hoisting mechanism and particularly to manually-operated hoisting mechanism, such as that used in portable elevators or tiering machines for raising the load-carrying platform; and an object of this invention is to provide a manually-operated hoisting mechanism which will safeguard the operator from injury due to the unexpected backward throw of the crank used by him 15 in winding up the mechanism. It is an important feature of this invention that the crank during the winding-up operation forms a connection between the winding-shaft and the pawl-controlled ratchet-wheel. 20 In the drawings illustrating the principle of this invention and the best mode now known to me of applying that principle, Figure 1 is a side elevation of so much of a hoisting mechanism of a tiering machine as 25 is necessary to illustrate this invention; Fig. 30 2 is a view looking in the direction of the arrow A in Fig. 1; Fig. 3 is a detail showing the ratchet disk in elevation; Fig. 4 is a section on the line 4—4 of Fig. 3; and Fig. 5 shows in perspective the square-headed operating crank. 35

The side standards or uprights *a* are connected by a cross-beam *b* which supports the auxiliary frame-members *c*, *d*, that carry the 40 outer ends of the shafts of the drum and the gears controlling the same and the brake mechanism therefor. The drum *e* is mounted fast upon the windlass-shaft *f* to which the larger spur-gear *g* is keyed. With the 45 latter meshes the pinion *h* keyed upon the same shaft *i* with the smaller spur-gear *j* that meshes with the pinion *k* keyed upon the upper winding shaft *m*. It will be obvious that by turning either of the shafts, 50 *i*, *m*, the windlass-drum *e* may be turned in a direction that will cause the cable *n* to be wound upon the same, whereby the load will be raised, the train of gearing hereinbefore referred to serving as an interme-

diary for the transmission of the power applied to the shaft. Each of the shafts *i*, *m*, is formed with a non-circular (e. g., squared) end *o* that projects beyond the outer face of the auxiliary upright *c*; and since the construction and arrangement of the outer ends of these two shafts (which may be designated as winding-shafts) is the same, it will suffice to describe one of them. At the base of the squared portion *o* of the winding-shaft, there is formed upon the same a collar *p* which is shaped to fit in annular groove *q* formed inside of the hub *r* of the ratchet wheel *s*; this collar prevents the latter from slipping off the shaft outwardly, while the upright *c* prevents its movement inwardly lengthwise of the shaft. This ratchet wheel *s* is loosely or idly mounted upon the winding-shaft, which is free to turn freely within the hub of the ratchet-wheel *s* save when the operating 70 crank *t* is in operative position, as will be more particularly set forth hereinafter. The ratchet-wheel *s* is further formed with ratchet teeth *s'* which are normally engaged by a spring-controlled pawl *u* pivotally mounted upon the upright *c*; hence, retrograde movement of the ratchet wheel *s* is prevented at all times by this pawl, but forward movement of the ratchet wheel is at 75 all times free and unrestrained. Within the hub *r* of the latter there is formed a cavity or recess *v* the wall of which is non-circular and therefore adapted and designed to interlock with the outer wall or faces of the head *t'* of the operating crank *t*, which is formed 80 with a socket *t''* within which fits snugly the squared end *o* of the winding-shaft (Fig. 1), when the crank *t* is in operative position; and when the crank *t* is in the latter position, it will be obvious from what has 85 already been said that the squared head *t'* of the crank *t* can not turn upon the winding-shaft and also cannot turn within the recess *v* of the hub *r* of the ratchet *s*; from which it follows clearly that, by putting his 90 crank in operative position, the workman interlocks the winding shaft with the ratchet *s* idly-mounted thereon, and that, when he turns the crank *t* to wind up the cable *n*, the winding-shaft and the ratchet *s* thereon 95 will turn with the crank as a single system; and, conversely, when the crank *t* is disengaged from the winding-shaft, it (the shaft) 100

is free to turn within the hub *r* unrestrained save for the retarding influence of the brake mechanism, which will now be described.

Upon the upper winding-shaft *m* there is keyed a brake-disk *z* in a groove in the rim of which there fit the shoes of a pair of brake-jaws *2* the upper ends of which are normally held apart by the coil-spring *3* wound around a cam-shaft *4* which carries cams *5* adapted to rub against cam-rollers *6* mounted upon lugs *7* projecting from the upper ends of the brake-arms *2* the lower ends of which are connected by the bolt *8*. Upon one end of the brake-controlling cam-shaft *4* there is fastened a brake-handle *9* by throwing which the brake-jaws *2* may be set or released at will. Upon the upper shaft *m* there is mounted fast a pawl-carrier *w* which carries a pivotally-mounted pawl *u* the toe of which is arranged to engage the internal ratchet-teeth *y* formed on the brake-disk *z*. When it is desired to pay out the cable *n* and thereby lower away the load, the workman pulls the brake-handle *9* toward him into the dotted-line position of Fig. 1, whereby he sets the brake so firmly that the pull of the load upon the cable *n* cannot turn the winding-shaft *m* in a retrograde or counter-clockwise direction. He next removes the crank *t* from within the hub *r* of the ratchet-wheel *s* and from off the non-circular end *o* of the winding-shaft *m*, whereby the connection between the latter and the ratchet-wheel *s* is destroyed and the holding effect or action of the pawl *u* upon the shaft is lost. The workman now manipulates the brake-handle *9* so as to lower away the load at the proper speed, keeping the load ever under control by means of the brake. It will be understood that the particular type of brake is immaterial; a strap-brake such as is shown and described in the McCarthy United States Patents Nos. 826,877 and 854,961 may be used equally well, for example.

In accordance with the provisions of the Patent Statutes, I have described the principle of operation of my invention, together with the apparatus which I now consider to represent the best embodiment thereof; but I desire to have it understood that the apparatus shown is only representative and that the invention can be carried out by other means.

55 I claim:

1. A hoisting mechanism including a winding shaft; locking mechanism for holding said shaft against retrograde rotation, while permitting forward rotation thereof; said locking mechanism including an operating device for giving said shaft forward rotation, said device being free to be slipped into and out of engagement with said shaft and mechanism and shaped to interlock the same when engaged therewith and to render

said mechanism operative and being freely removable from said shaft to break the interlocking engagement thereof with said mechanism and to render the latter inoperative.

2. A hoisting mechanism including a winding shaft; locking mechanism for holding said shaft against retrograde rotation, while permitting forward rotation thereof; said locking mechanism including an operating device for giving said shaft forward rotation, said device being free to be slipped into and out of engagement with said shaft and mechanism and shaped to interlock the same when engaged therewith and to render said mechanism operative and being freely removable from said shaft to break the interlocking engagement thereof with said mechanism and to render the latter inoperative; and brake mechanism for controlling the retrograde rotation of said shaft, after said device is disengaged therefrom.

3. A hoisting mechanism including a winding shaft; locking mechanism for holding said shaft against retrograde rotation, while permitting forward rotation thereof; said locking mechanism including an operating crank for giving said shaft forward rotation, said crank being free to be slipped into and out of engagement with said shaft and mechanism and shaped to interlock the same when engaged therewith and to render said mechanism operative and being freely removable from said shaft to break the interlocking engagement thereof with said mechanism and to render the latter inoperative.

4. A hoisting mechanism including a winding shaft; a rotatable member loosely mounted thereon; a locking device for holding said member against retrograde rotation, while permitting forward rotation thereof; said locking device including an operating device for giving said shaft forward rotation, said operating device being free to be slipped into and out of engagement with said shaft and member and shaped to interlock the same when engaged therewith and to render said member and locking device operative and being freely removable from said shaft to break the interlocking engagement thereof with said member and to render the latter inoperative.

5. A hoisting mechanism including a winding-shaft; a ratchet-wheel idly mounted thereon; a pawl for controlling said ratchet wheel; an operating crank which is adapted to interlock said wheel with said shaft and which is freely removable to destroy the interlock therebetween and thereby to permit the retrograde movement of said shaft; and brake mechanism for holding the latter against rotation at the will of the operator.

6. A hoisting mechanism including a winding shaft; a rotatable member loosely mounted thereon; a locking device for holding said member against retrograde rotation, while permitting forward rotation thereof; said locking device including an operating device for giving said shaft forward rotation, said operating device being free to be slipped into and out of engagement with said shaft and member and shaped to interlock the same when engaged therewith and to render said member and locking device operative and being freely removable from said shaft to break the interlocking engagement thereof with said member and to render the latter inoperative; and brake mechanism for controlling the retrograde rotation of said shaft, after said operating device is disengaged therefrom.
- 10 7. A hoisting mechanism including a winding-shaft; an operating crank; and a locking device arranged to permit the rotation in a forward direction; said crank being adapted to interlock said device and shaft operatively and being freely removable to release said shaft from the locking action of said device and thereby permit the retrograde movement of said shaft.
- 20 8. A hoisting mechanism including a winding-shaft; a rotatable member loosely mounted on the same; a device for preventing retrograde movement of said member; and means for turning said shaft; said means being adapted to interlock said shaft with said member and being removable to destroy the interlock therebetween and thereby to permit the retrograde movement of said shaft.
- 25 9. A hoisting mechanism including a winding-shaft; a ratchet-wheel idly mounted thereon; a pawl for controlling said ratchet wheel; and an operating crank which is adapted to interlock said wheel with said shaft and which is freely removable to destroy the interlock therebetween and thereby to permit the retrograde movement of said shaft.
- 30 10. A hoisting mechanism including a winding shaft; locking devices for holding the same against retrograde rotation, one of said devices being mounted loosely on said shaft; said locking device including a crank for turning the latter, said crank being shaped to interlock with said shaft and one of said locking devices.
- 35 11. A hoisting mechanism including a winding shaft; pawl - and - ratchet mechanism one member of which is mounted on said shaft; a crank for turning the latter, said crank being shaped to interlock with said shaft and member and being freely removable to break the interlocking connection therebetween; and brake mechanism for holding said shaft against retrograde rotation, when the crank is removed therefrom.

Signed at Jersey City New Jersey, this 22nd day of December, A. D. 1913, in the presence of the two undersigned witnesses.

WILLIAM EDWARD BOEHCK.
